(57) **CLAIM**

The ornamental design of a mug for liquids, as shown and described.

DESCRIPTION

FIG. 1 is a top perspective view of a first embodiment of a mug for liquids, showing my new design;

FIG. 2 is a bottom perspective view thereof;

FIG. 3 is a top view thereof;

FIG. 4 is a bottom view thereof;

FIG. 5 is a front view thereof;

FIG. 6 is a back view thereof;

FIG. 7 is a left side view thereof;

FIG. 8 is a right side view thereof;

FIG. 9 is a top perspective exploded view thereof;

FIG. 10 is a bottom perspective exploded view thereof;

FIG. 11 is a front exploded view thereof;

FIG. 12 is a top perspective view of a second embodiment of a mug for liquids, showing my new design;

FIG. 13 is a bottom perspective view thereof;

FIG. 14 is a top view thereof;

FIG. 15 is a bottom view thereof;

FIG. 16 is a front view thereof;

FIG. 17 is a back view thereof;

FIG. 18 is a left side view thereof;

FIG. 19 is a right side view thereof;

FIG. 20 is a top perspective exploded view thereof;

FIG. 21 is a bottom perspective exploded view thereof; and,

FIG. 22 is a front exploded view thereof.

The broken lines in the drawing views represent unclaimed portions of a mug for liquids, which are included for the purpose of illustrating unclaimed environment only, and form no part of the claimed design.

1 Claim, 14 Drawing Sheets
